UNITED STATES PATENT OFFICE.

FRIEND A. RUSS, OF GREENWICH, AND JOHN B. RUSS, OF SHELTON, CONNECTICUT.

LOOP AND BUTTON CLASP.

No 902,916.

Specification of Letters Patent.

Patented Nov. 3, 1908.

Application filed January 31, 1908. Serial No. 413,570.

To all whom it may concern:

Be it known that we, FRIEND A. RUSS, residing at Greenwich, in the county of Fairfield and State of Connecticut, and JOHN B. RUSS, residing in Shelton, in the county of Fairfield and State of Connecticut, both citizens of the United States, have invented a new and useful Improvement in Loop and Button Clasps, of which the following is a specification.

10 This invention relates to loop and button clasps and its object is to provide a loop member to which a button carrying tab of minimum length may be attached without 15 resorting to the expedient of sewing or stitching.

With this and other objects in view our invention consists in the details of construction and manner of operation more fully 20 described in the following description and accompanying drawings in which like reference characters refer to corresponding parts.

In the drawings: Figure 1 is a front view 25 of the clasp showing a fragmentary portion of the supporting strap partly broken away; Fig. 2, a longitudinal section of Fig. 1, and Fig. 3, a longitudinal section of the loop member shown in Figs. 1 and 2 before the 30 tab is attached.

Our device generally consists of a loop member A, a supporting strap or webbing B and a tab C carrying the button D, all of the parts being shown enlarged for the purpose of clearness. The loop member A is made out of sheet metal blanked and struck up to form the loop proper 1 having the usual elongated button opening contracted at its lower extremity to embrace the neck 40 of the button D. Mounted on the upper extremity of the loop 1 is the base 2 made in skeleton form its upper extremities being connected by the attaching bar 3 around which passes the supporting strap B. Bridging the base 2 between the loop 1 and the attaching bar 3 is a flat narrow bar 4 having its lower projecting side bent rearwardly at an angle to form the outwardly projecting lip 5 having transversely disposed edge 6 which is adapted to be folded back on the bar 4 to grip and confine the end of the tab C. All of the parts of the loop member A, with the exception of the flat bar 4 and its projecting lip 5, have their face portions 50 struck up to give the necessary body and

strength to the frame, and at the same time to enable the loop member to present the skeleton like and ornamental appearance of a heavy metal or wire device bridged by a narrow, flat and countersunk sheet metal 60 part.

The tab C has a stud or button D mounted on one extremity and has its other extremity confined and compressed between the lip 5 and the bar 4. To assemble the tab and loop member the latter is placed in a press suitably adapted for this purpose so that the lip 5 projects upwardly. The extremity of the tab is then passed over the base until it strikes the bottom of the lip which acts as a 70 guide or stop. The lip is then pressed or swaged down by the press across the surface of the tab compressing and pinching the same tightly between the lip and the corresponding portion of the bar 4; thus the tab 75 is gripped across its extremity between two flat gripping surfaces without being pierced, cut or weakened at this point. When the loop is drawn over the button to fasten a garment or to effect other clasping action, 80 as shown in Figs. 1 and 2, the tab is drawn taut over the straight edge 6 of the lip, which edge not only acts as a rigid support to keep the tab uniformly spread, but also by its frictional engagement or binding action 85 relieves the clenched extremity, to a greater or less degree, of any strain or pull tending towards displacement. By mounting the tab in this manner the so called rustless effect is produced, that is, the tape and 90 supporting strap are interposed between the metal loop and the garments or body of the wearer so that the loop is prevented from being exposed to moisture due to perspiration.

Having now described our invention what we claim and desire to protect by Letters Patent is:

In a loop and button clasp the combination with a tab having a button mounted on one extremity, of a sheet metal loop member provided with an opening for the passage of the head of said button having its lower portion contracted to embrace the neck of said button, a skeleton base mounted on said loop member above said opening having its upper extremities connected by an attaching member adapted to be carried by a supporting strap or webbing, and a flat bar bridging said base between said attaching member 110

and button opening, the said bar being provided with an integral lip folded back on the rear side of said bar to grip the free end of said tab, whereby when the neck of the button is embraced by the contracted portion of the button opening the said tab is drawn taut and held uniformly spread by the edge of said lip.

In testimony whereof we have hereunto

set our hands this 17th day of January, 10
A. D. 1908.

FRIEND A. RUSS.
JOHN B. RUSS.

Witnesses to the signatures of Friend A.
and John B. Russ:
